(57) **CLAIM**

The ornamental design for a windshield cover as shown and described.

DESCRIPTION

FIG. 1 is a top perspective view of a windshield cover, showing our new design.

FIG. 2 is a top plan folded view thereof.

FIG. 3 is a bottom perspective folded view thereof showing the extension flaps folded inward.

FIG. 4 is a left side elevational view thereof.

FIG. 5 is a right side elevational view thereof.

FIG. 6 is a front elevational view thereof.

FIG. 7 is a rear elevational view thereof.

FIG. 8 is a top plan open view thereof showing the extension flaps folded outward; and,

FIG. 9 is a bottom plan open view thereof showing the extension flaps folded outward.

The broken lines illustrate portions of the windshield cover that form no part of the claimed design.
